THERMOMETER HOLDER

Ernest Oscar Valane, Oak Terrace, Minn., assignor of one-half to G. A. Goff, Hennepin County, Minn.

Application July 19, 1937, Serial No. 154,406

1 Claim. (Cl. 248—229)

This invention relates to a holding device and while the invention might have various applications to hold different kinds of articles, one specific article intended to be held is a thermometer such as used in hospitals.

It is the common practice in the modern hospital to have a thermometer in the patient's room for taking the temperature of the patient at desired intervals. One common way of holding the thermometer has been to secure a receptacle for holding the thermometer to the bedpost by adhesive tape. This mars and disfigures the post and the application and removal of the tape objectionably jars the patient. It is desirable to have a simple and efficient means which can be easily and quickly applied to and removed from the supporting means without shock. It is also desirable to have a holder comprising a container, which container can be readily removed.

It is an object of this invention therefore, to provide an extremely simple, efficient and easily operated holder for a thermometer or similar article.

It is a further object of the invention to provide a holder for a thermometer or similar article which can easily be placed upon a bed post to be supported thereby and which conveniently and removably holds a container.

It is more specifically an object of the invention to provide a holder for a thermometer or similar article comprising a tubular open-topped container and a bracket preferably made of one piece of sheet material having pairs of resilient arms adapted to clamp the bed post and resilient means embracing and holding said container.

These and other objects and advantages of the invention will be fully set forth in the following description made in connection with the accompanying drawing in which like reference characters refer to similar parts throughout the several views and in which:

Fig. 1 is a perspective view of a portion of a bed showing the invention applied to a part of said bed;

Fig. 2 is a perspective view of the holder; and

Fig. 3 is a horizontal section taken substantially on line 3—3 of Fig. 2 as indicated by the arrows.

Referring to the drawing, a device is shown comprising a container 10 having an open top and a closed bottom and an elongated chamber therein. While this holder might be made in various ways or of various forms, in the embodiment of the invention illustrated, it is shown as made of a tube, preferably of glass, having a

rounded lower end. Said container 10 has in the bottom thereof a small quantity of some yielding material 11 which may be of fabric material such as cotton or may be of sponge or sponge rubber. Said container 10 is supported in a bracket designated generally as 12. While bracket 12 might be variously formed, in the embodiment of the invention illustrated it is shown as made from one piece of sheet material. Said material is preferably metal and the device conveniently may be made of brass, sheet aluminum, or any sheet material suitably plated. Bracket 12 has at its top and bottom a pair of resilient arms 12a, the same being oppositely disposed and substantially semi-cylindrical in form, said pairs of arms 12a having a common axis. Arms 12a may have secured to their concave sides a sheet of some soft yielding material 13 such as rubber or soft fabric. A narrow strip of material 12b extends between the arms 12a and said strip has extending therefrom intermediate said arms 12a another pair of arms 12c. Arms 12c extend substantially oppositely to arms 12a and are also of substantially semi-cylindrical form and oppositely disposed. Arms 12c are constructed and arranged to embrace and clamp the container 10. Bracket 12 also has at its lower end a small plate 12d which extends in the same direction as arms 12c and forms a support for the bottom of container 10.

In operation, the device may be supported upon the bed post 15a of the bed 15 and it will be seen from Fig. 1 that arms 12a embrace the post 15a and said arms grip and clamp said post so that bracket 12 is supported securely thereon. There will be no marring of the post due to the lining 13 and the bracket can be placed on and removed from the post with little effort. Container 10 is firmly supported in the arms 12c and on the plate 12d. Container 10 is therefore supported in vertical position close to the post 15a. The thermometer will be placed in the container 10 and will have its lower end, preferably the mercury end resting on the material 11. The thermometer shown as 16 in Fig. 1, will protrude slightly from the top of container 10 so that it may be very easily taken hold of for removal.

From the above description it is seen that applicant has provided an extremely simple, highly efficient and inexpensive device for supporting a thermometer. The device can be easily changed in position from one post to another and can thus be placed within reach of the patient when this is desired. It is obvious that the device may be supported at any height on the post and the same will remain in the position in which it is

placed. The device is small and compact and is not in the way of either the nurse, patient or other persons. The device has been amply demonstrated in actual practice and found to be very successful and efficient.

5 It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claim.

10 What is claimed is:

A thermometer holder having in combination, a tubular container having an open upper end, a bracket formed of one piece of sheet material having at its top and bottom oppositely disposed resilient substantially semi-cylindrical arms 5 adapted to embrace and clamp a bed post, said bracket having spaced resilient oppositely disposed substantially semi-cylindrical arms disposed between said first mentioned arms and facing substantially oppositely thereto adapted 10 to embrace said container and a horizontal projection at its lower end forming a rest for the bottom of said container.

ERNEST OSCAR VALANE.
